CLAIM

The ornamental design for a storage rack, as shown and described.

DESCRIPTION

FIG. 1 is a front elevational view of the storage rack, embodying our design;

FIG. 2 is a front elevational view thereof;

FIG. 3 is a top plan view thereof, the bottom view thereof being flat and unornamented;

FIG. 4 is a right-side elevational view thereof, the left-side elevational view being a mirror-image thereof; and,

FIG. 5 is a back elevational view thereof.

The material symbol illustrated partially on the screen element in FIGS. 1, 2, and 5 is understood to extend across the entire surface of the screen element.

The broken lines in the drawing figures are for environmental purposes only and form no part of the claimed design.
